SEALED CONTAINER

Leo Harold Brodrick, New York, N. Y.

Application July 10, 1934, Serial No. 734,478

17 Claims. (CL. 229—6)

This invention relates to containers, and more particularly to sanitary sealed containers.

By way of specific illustration of the invention, but not in limitation thereof, the invention will be described as applied to a box or container used for face powder. Such containers ordinarily comprise a cylindrical bottom or lower part open at the top, a cylindrical cover or top open at the bottom and fitting over the lower part, and a drum or annular band forming a part of the bottom or lower half of the container and operating to hold in place at the top of the lower half of the container a frangible sealing paper frequently made of a transparent material, thus exposing the powder to inspection without contamination. Such containers as heretofore constructed are not truly sift-proof, for powder may sift between the drum and bottom, and in many cases the drum actually shifts relative to the bottom unless the parts are cemented together which, however, is a slow, troublesome, and expensive operation.

The primary object of my invention is to generally improve sanitary sealed containers. More particular objects are to prevent shifting of the drum within the container and to make the lower part of the container truly sift-proof without the use of cement or adhesive; to reduce the initial cost of the container, and, independently of initial cost, to reduce the expense attendant upon assembly and filling the container with powder; to provide a container the disassembled parts of which are in compact relation for shipment and convenient relation for handling, there being in effect only two parts to be shipped and handled; although the container is really a three-part container; and, finally, to produce a container of increased strength and rigidity and of improved appearance.

To the accomplishment of the foregoing and other objects which will hereinafter appear, my invention consists in the combination of container elements, and their relation one to another, as hereinafter are more particularly described in the specification and sought to be defined in the claims. The specification is accompanied by a drawing in which:

Fig. 1 is a perspective view of an opened container embodying features of my invention;

Fig. 2 is a vertical section through a part of the same;

Fig. 3 is a vertical section through the drum of my container;

Fig. 4 is a vertical section illustrating the mode of assembly of the container; and

Fig. 5 is a section through a modified form of the invention.

Referring to the drawing and more particularly to Fig. 1 thereof, the container comprises a lower part made up of a drum D closed at its upper end by a frangible membrane M, and at its lower end by a base or bottom B, and an upper part or cover C adapted to slip over the lower part with a slip fit. The membrane M may be made transparent, thus exposing the contents for visual inspection without loss or contamination. The membrane is readily broken by the purchaser who then relies upon the slip cover C to close the container.

The drum D is best shown in Fig. 3 and comprises a cylindrical wall closed at one end by a membrane M but open at its opposite end. The open end is preferably curled inwardly to form a bead 12. The drum is shown in Fig. 3 with its right side up, but it is inverted for the filling operation. Thus, referring to Fig. 4, the drum D is shown in inverted condition, the membrane M being at the bottom. The drum is filled with a quantity of the product being packaged, for example the face powder 14, whereupon the open end of the drum is closed by applying thereto the bottom B. This bottom is shaped to provide a peripheral undercut groove 16 which mates accurately with the bead 12, so that the bottom may be applied to the drum with a snap fit or engagement. The close fit of the parts, preferably maintained by the natural expansion of the curl 12, results in a tight sift-proof joint. Use of a cement or adhesive is unnecessary and may be dispensed with.

The assembled drum and bottom then form the lower half of the package shown in Fig. 1 and may be inverted to permit the application thereto of a slip cover C, as is shown in Fig. 2. In practice, the assembly of the package is even further simplified by placing the drum D within the cover C during manufacture of the container and prior to shipment of the container to the powder manufacturer. The nested drum and cover shown in Fig. 4 are shipped and handled as a single unit. The container is, in effect, only a two-part container, and one of the two parts is comparatively flat and disc-like. This is to be contrasted with a prior art three-part container each of the parts of which is substantially equal in size to the complete package. The height of the drum D is made equal to or slightly greater than the internal height of the cover, thus exposing the curled edge of the drum. A measured quantity of the powder is placed in the double- 55

walled chamber, and the bottom is then applied and pressed home, as is indicated in Fig. 4. The complete package is thus filled and assembled conveniently and rapidly, the assembly involving only a single quick operation.

Considering the arrangement in greater detail, the box is made generally of paper, except for the bottom. The drum D comprises an annular band of rough or unfinished paper board, 10 cardboard, or like fibrous material, which may be cut from a continuous tube and curled to form the bead 12, in accordance with known methods. The membrane M is thin and readily punctured. It may be made transparent or not, according to the wishes of the purchaser. It is stretched over the end of the drum, and its edges are folded downwardly about the outer wall of the drum. A band 18 of finishing paper is then cemented around the exterior of the drum, serving the dual purpose of holding the membrane M in place and of finishing the exposed exterior of the drum.

In the form shown in Figs. 1 through 4, the bottom B is made of thin sheet metal. This sheet metal is pressed to form an upwardly dished bottom 20 and is spun or otherwise shaped to provide the under-cut annular groove or shoulder 16. The disc projects outwardly to form a flange 22, and a rounded and stiffened edge is obtainable even when using thin sheet metal by folding the edge inwardly, as indicated at 24. This fold is preferably made upwardly, and the edge is terminated at such a point as to form a continuation of the groove or recess 16 which receives and encompasses the beaded edge 12. The edge of the sheet metal is concealed by the round edge of the drum, and, conversely, the lowermost edge of the finishing paper 18 is concealed by the inwardly folded metal edge. It will be understood, however, that if desired the edge of the base may be otherwise folded or may even be left unfolded.

The slip cover C may be of conventional type and requires no detailed description. It comprises a cylindrical side wall 26 closed at one end by a top wall 28. The exposed walls are coated with a finishing paper. The slip cover fits the side wall of the drum with a slip fit. The lower edge of the cover is protected by the outwardly projecting flange of the bottom. As has already been mentioned, the height of the drum is preferably made substantially equal to the internal height of the cover, so that the bottom may be applied while the drum is within the cover, but if the bottom is applied to the drum alone (the cover being added later) the drum may, of course, be made substantially less in height than the cover.

A modified form of container embodying features of my invention is shown in Fig. 5. This container is generally similar to that heretofore described in that it comprises a drum D the upper end of which is closed by a frangible membrane M, and the lower end of which is closed with a snap engagement by a bottom B. In this case, however, the bottom is made of a moldable composition rather than sheet metal. It may be made, for example, of a synthetic resin such as the condensation products of phenol or 70 urea. It is molded to a shape which provides the desired peripheral undercut groove 16', and it may, of course, also include the marginal flange 22'.

The drum D may be like that heretofore described, but as shown differs in that the finish-

ing paper extends around the curl, it being applied after the sealing membrane but before forming the curl. The cover C may also be made like that heretofore described, but the particular cover shown differs in that the top 30 is secured to the side wall 32 in abutting relation by means of the covering paper 34. In the form shown in Figs. 1 through 4, the upper edge of the side wall 26 is curled at 36, and the top 28 is held by the curl or bead 36. Various other forms of cover may be used, and the exact nature of the cover forms no part of the present invention. However, I may mention that the cover shown in Figs. 1 through 4 possesses an advantage when the bottom is applied to both the drum and cover, as shown in Fig. 4, because the cover is adapted to rest on a flat surface and to support the drum against the pressure of the bottom while the bottom is being pressed into place. With a cover such as is shown in Fig. 5, it is desirable that the work table be recessed to mate with the convex top 30 of the cover, so that the pressure caused when applying the cover will not tend to deform or flatten the cover.

It will be understood, however, that the pressure in question is not excessive because the bottom is preliminarily tilted as shown at Fig. 4, thus bringing the bead and groove into mating relation at one side of the bottom. It is both difficult and undesirable to force the bottom flatly downwardly against the entire beaded edge because the parts are preferably mated together very tightly. In fact, it is practically impossible to pry the drum from the bottom once it has been snapped into place. 30 33

It is believed that the mode of constructing and using, as well as the many advantages of my improved sanitary sealed container, will be apparent from the foregoing detailed description thereof. It will further be apparent that while I have shown and described my invention in preferred forms, many changes and modifications may be made in the structures disclosed, without departing from the spirit of the invention, defined in the following claims.

I claim:

1 claim.

1. A three-part container comprising a cylindrical drum closed at its upper end by a frangible membrane but open at its lower end, a relatively thick rigid disc-like bottom for said drum, said bottom having an outwardly projecting flange and being arranged upon application with pressure from the outside to mechanically interlock with said drum and bottom for permanently securing said bottom to said drum without the use of adhesives, and a readily removable slip cover comprising a top wall and a cylindrical side wall dimensioned to slip over the top of the drum to the bottom flange. 50 55 60

2. A three-part container comprising a cylindrical drum closed at its upper end by a frangible membrane but open at its lower end, a bottom arranged to fit the open end of the drum and upon application with pressure from the outside to permanently mechanically interlock therewith with a snap engagement and without necessitating the use of adhesive, said bottom having an outwardly projecting flange, and a readily removable slip cover comprising a top wall end a cylindrical side wall, said cover being dimensioned to slip over the top of the drum to the bottom flange. 70

3. A three-part container comprising a cylindrical drum, the lower end of said drum being 75

curled to form an edge bead, a disc-like bottom having an annular undercut groove adapted to mate snugly with the curled edge of the drum, said bottom having a flange projecting outwardly beyond the drum, and a slip cover comprising a top wall and a cylindrical side wall, said cover being dimensioned to slip over the drum to the bottom flange.

4. A three-part container comprising a tubular drum closed at its top end by a frangible membrane, the lower end of said drum being curled to form an edge bead, a disc-like bottom having an annular undercut groove adapted upon application with pressure from the outside to mate snugly and permanently with a sift-proof snap fit against the curled edge of the drum, and a readily removable slip cover dimensioned to slip over the top end of the drum.

5. A three-part container comprising a cylindrical drum closed at its top end by a frangible transparent membrane, the lower end of said drum being curled inwardly to form an edge bead, a disc-like bottom having an annular undercut groove adapted upon application with pressure from the outside to mate snugly with a snap fit against the curled edge of the drum, said bottom having a flange projecting outwardly beyond the drum, and a slip cover comprising a top wall with a cylindrical side wall, said cover being dimensioned to slip over the drum to the bottom flange.

6. A three-part container comprising a tubular drum closed at its top end by a frangible membrane, the lower end of said drum being curled to form an edge bead, a disc-like bottom made of sheet metal shaped to form a peripheral undercut or groove adapted upon application with pressure from the outside to mate with the curled edge of the drum for permanent attachment thereto, and a slip cover dimensioned to slip over the drum.

7. A three-part container comprising a cylindrical drum closed at its top end by a frangible membrane, the lower end of said drum being curled inwardly to form an edge bead, a disc-like bottom made of sheet metal dished upwardly to form a peripheral undercut groove mating with the curled edge of the drum, the edge of the sheet metal projecting outwardly and being turned inwardly to form a smooth marginal flange and a slip cover comprising a top wall and a cylindrical side wall, said cover being dimensioned to slip over the drum to the bottom flange.

8. A three-part container comprising a cylindrical drum open at its bottom end and closed at its top end by a frangible membrane, the lower end of said drum being curled to form an edge bead, a molded disc-like bottom shaped to form a peripheral undercut groove dimensioned upon application with pressure from the outside to mate and to permanently mechanically interlock with the aforesaid curled edge of the drum, and a readily removable slip cover dimensioned to slip over the top end of the drum.

9. A three-part container comprising a cylindrical drum open at its bottom end and closed at its top end by a frangible membrane, the lower end of said drum being curled inwardly to form an edge bead, a disc-like bottom molded of synthetic resinous material and shaped to form a peripheral undercut groove dimensioned upon application with pressure from the outside to mate and to permanently mechanically interlock with the aforesaid curled edge of the drum and to further form an outwardly projecting

marginal flange, and a readily removable slip cover comprising a top wall and a cylindrical side wall, said cover being dimensioned to slip over the top end of the drum to the bottom flange.

10. A three-part sanitary sealed container for face powder or the like adapted to be shipped and handled in two parts, one of said parts comprising a drum readily removably nested within a cover, and the other part comprising a bottom, said drum comprising a cylindrical side wall closed at one end by a frangible sealing membrane and open at the other end and curled at said open end, and said bottom being provided with an annular undercut groove dimensioned upon application with pressure from the outside to mate and to mechanically interlock with the curled edge of the drum within the cover.

11. A three-part sanitary sealed container for face powder or the like adapted to be shipped, filled, and handled in two parts, one of said parts comprising a drum removably nested within a cover, and the other part comprising a bottom, said cover comprising a cylindrical side wall closed at one end by an end wall and open at its opposite end, said drum comprising a cylindrical side wall closed at one end by a frangible sealing membrane and open at the other end and inwardly curled at said open end, said drum being so received within said cover that the open edge of the drum is exposed at the open edge of the cover, said bottom being provided with an annular undercut groove dimensioned upon application with pressure from the outside to mate and to mechanically interlock snugly with the curled edge of the drum, and a flange on said bottom projecting outwardly from said undercut groove.

12. A three-part container for face powder or the like comprising a cylindrical drum made of unfinished cardboard closed at its top end by a frangible membrane stretched over said end and folded downwardly about the cylindrical side wall, the lower end of said drum being curled inwardly to form an edge bead, a finishing band of paper cemented around the drum to hold the membrane in place and to give the exposed wall of the drum a finished appearance, a disc-like bottom having an annular undercut groove adapted upon application with pressure from the outside to mate snugly with the curled edge of the drum, and a readily removable slip cover dimensioned to slip over the top end of the drum.

13. A three-part container comprising a cylindrical drum made of unfinished cardboard closed at its top end by a frangible membrane stretched over said end and folded downwardly about the cylindrical side wall, the lower end of said drum being curled inwardly to form an edge bead, a finishing band of paper cemented around the drum to hold the membrane in place and to give the exposed wall of the drum a finished appearance, a disc-like permanently attached bottom having an annular undercut groove adapted to mate snugly with a snap fit against the curled edge of the drum, said bottom having a flange projecting outwardly beyond the drum, and a readily removable slip cover comprising a top wall and a cylindrical side wall, said cover being dimensioned to slip over the drum to the bottom flange.

14. A container for face powder or the like, comprising a lower half and a mating upper half acting as a removable cover for the lower half

- and dimensioned to fit onto the lower half with a slip fit, the side wall of the lower half being formed of paper, cardboard, or like fibrous material and being entirely closed at the bottom by a closure member having a peripheral groove sprung into engagement with a bead or annular projection provided at the lower edge of the side wall of the lower half of the container.
15. A container for face powder or the like, comprising a lower half and a mating upper half acting as a removable cover for the lower half and dimensioned to fit over the lower half with a slip fit so as more or less entirely to enclose the side walls of the lower half, the lower half including a side wall formed of paper, cardboard, or like fibrous material and being entirely and permanently closed at the bottom by a one-piece closure member of more durable material, said closure member being formed with a peripheral flange underlying the side wall and a peripheral groove or under-cut which is mechanically interlocked with the side wall, said side wall and closure member being preformed prior to assembly in such fashion that they may be brought into mechanically interlocking engagement by simply pressing or snapping the parts together.
16. A container for face powder or the like, comprising a lower half and a mating upper half acting as a removable cover for the lower half and dimensioned to fit over the lower half with a

slip fit and to substantially entirely enclose the lower half, the lower half including a side wall formed of paper, cardboard, or like fibrous material entirely and permanently closed at the bottom by a one-piece closure member mechanically interlocked with the sidewall, said side wall having a preliminarily formed bead, and said closure member having a preliminarily formed groove or undercut adapted to receive the bead, the parts being so dimensioned that pressure is required to 10 effect interlocking of said bead and groove.

17. A container for face powder or the like, comprising a lower half and a mating upper half acting as a removable cover for the lower half and dimensioned to fit over the lower half with a 15 slip fit so as to substantially entirely enclose the lower half, said lower half being entirely and permanently closed at the bottom by a one-piece closure member mechanically interlocked therewith, the side wall of the lower half being curled 20 inwardly at its lower edge to form a bead, and said closure member having a peripheral undercut groove adapted to mate with the curled edge bead of the side wall, the parts being so shaped and dimensioned that they may be readily interlocked by merely pressing the parts together, yet 25 cannot be separated except with great difficulty or breakage of the parts of the container.

L. HAROLD BRODRICK. 30
